UNITED STATES PATENT OFFICE.

JOHN B. MORGAN, OF PHILADELPHIA, PENNSYLVANIA, ASSIGNOR TO THOMAS WISTAR BROWN AND SUSAN F. WHEELER, OF SAME PLACE.

DESIGN FOR WOVEN FABRIC.

SPECIFICATION forming part of Design No. 24,430, dated June 25, 1895.

Application filed May 20, 1895. Serial No. 549,999. Term of patent 7 years.

To all whom it may concern:

Be it known that I, JOHN B. MORGAN, a citizen of the United States, residing in Philadelphia, Pennsylvania, have invented a new and original Design for Woven Fabric, of which the following is a specification.

My design for a woven fabric is fully shown in the accompanying drawing, which represents sufficient of a piece of the fabric to illustrate the design.

My design comprises two stripes A and B, the latter being somewhat wider than the former, these stripes being separated from each other by intervening stripes of background D, and each of said stripes A and B being composed of a series of finer subordinate stripes.

The stripe A comprises a central wide stripe a flanked on each side by a narrow stripe b and beyond each of these stripes b is a narrow but somewhat wider stripe d similar to

the stripe A and beyond each of these stripes d is a wider stripe f similar to the stripe b.

The stripe B is composed of three stripes g, two somewhat narrower stripes h and a series 25 of fine stripes i, there being six of these fine stripes which flank the stripes g and also serve to separate the latter from the stripes h. All of the correspondingly lettered stripes forming the main stripe B are alike. 30

I claim—

The design for a woven fabric, substantially as described and as shown in the accompanying drawing.

In testimony whereof I have signed my 35 name to this specification in the presence of two subscribing witnesses.

JOHN B. MORGAN.
